UNITED STATES PATENT OFFICE.

JOHN R. HIRSH, OF SYRACUSE, NEW YORK.

DESIGN FOR A COAT-HOOK.

SPECIFICATION forming part of Design No. 26,791, dated March 28, 1897.

Application filed January 20, 1897. Serial No. 619,986. Term of patent 7 years.

To all whom it may concern:

Be it known that I, JOHN R. HIRSH, of Syracuse, in the county of Onondaga, in the State of New York, have invented and produced a new and original Design for Coat-Hooks, of which the following, taken in connection with the accompanying drawings, is a full, clear, and exact description.

In the drawings I show an isometrical view of my design complete, this view being deemed sufficient to properly illustrate the same.

The leading feature consists in a unitary design and has a base symmetrical in form, its corners rounded at one end and its opposite end terminating in an upturned hook, substantially as shown. There are offsets on each side, as shown, about midway of its

length, the whole forming a unitary article, and presents a pleasing effect upon the eye.

a is the base, having the corners rounded, ²⁰ as shown at *b*, and *c* is the hook terminating at the opposite end of the base, and *d* are the offsets on each side.

Having described my invention, what I claim, and desire to secure by Design Letters ²⁵ Patent, is—

The design for a coat-hook, substantially as herein described and shown.

In witness whereof I have hereunto set my hand this 9th day of December, 1896.

JOHN R. HIRSH.

In presence of—

MARY A. FRANKLIN,
HOWARD P. DENISON.
